UNITED STATES PATENT OFFICE.

FRANK H. PECK, OF GALVESTON, TEXAS.

TELEPHONE-TRANSMITTER DISINFECTOR.

961,369.

Specification of Letters Patent. Patented June 14, 1910.

Application filed August 18, 1909. Serial No. 513,501.

To all whom it may concern:

Be it known that I, FRANK H. PECK, a citizen of the United States, residing at Galveston, in the county of Galveston and State of Texas, have invented certain new and useful Improvements in Telephone-Transmitter Disinfectors, of which the following is a specification.

This invention relates to mouthpieces for telephone transmitters and more particularly to a detachable disinfecting cap adapted to form a closure for the open end of the mouthpiece and prevent the transmission of microbes or other germs lodged in the mouthpiece to the person using the telephone.

The object of the invention is to provide a comparatively simple and thoroughly efficient device of the character described, capable of being readily attached to or detached from the mouthpiece of the transmitter and by means of which the mouthpiece is rendered thoroughly sanitary.

A further object is to provide a detachable cap having a strip of cloth, paper or membrane secured thereto and saturated with a soluble germicide which will dissolve in the moist spray thrown out in talking and render the same sterile.

30 A further object is to provide novel means for locking the cap in position on the mouthpiece of the telephone transmitter.

A still further object of the invention is generally to improve this class of devices so as to increase their utility, durability and efficiency, as well as to reduce the cost of manufacture.

Further objects and advantages will appear in the following description, it being understood that various changes in form, proportions and minor details of construction may be resorted to within the scope of the appended claims.

For a full understanding of the invention and the merits thereof and also to acquire a knowledge of the details of construction and the means for effecting the result, reference is to be had to the following description and accompanying drawings, in which:

50 Figure 1 is a perspective view of a telephone transmitter provided with a sanitary cap constructed in accordance with my invention; Fig. 2 is a vertical sectional view of the same; Fig. 3 is a perspective view of the 55 cap with the disinfecting strip and locking

member detached and shown in position to enter the rim of the cap.

Corresponding and like parts are referred to in the following description and indicated in all the views of the drawings by the same reference characters.

The sanitary disinfecting cap forming the subject matter of the present invention is principally designed for attachment, to the mouthpiece of a telephone transmitter and by way of illustration is shown in connection with a desk telephone in which 5 designates the standard, 6 the transmitter and 7 the mouthpiece having its inner end reduced and threaded at 8 for engagement with a corresponding opening in the transmitter.

The device comprises an annular supporting rim 9 having its outer face inclined toward the center of the mouthpiece 7, at 10 to 75 form an inner circumferential flange 11 and its outer marginal edge provided with a flange 12 adapted to engage the exterior wall of the mouthpiece, as best shown in Fig. 2 of the drawings. The metal forming the 80 flange 12 is bent outwardly to form a circumferential seating groove 13 adapted to receive a locking member 14. The locking member 14 is preferably formed of a single length of spring wire, one end of which 85 is bent laterally to form an angularly disposed finger piece 15 adapted to enter a recess 16 formed in the flange 12 and intersecting the groove 13.

Interposed between the rim 9 and the adjacent edge of the mouthpiece 7, is a disinfecting cap 17, the latter being formed of cloth, paper, membrane or other suitable material saturated with a soluble germicide which will dissolve in the moist spray 95 thrown out in talking and render the same sterile. The cloth or membrane 17 is preferably reinforced and strengthened by an annular strip of paper or other suitable material 18, which latter is forced against the adjacent edge of the mouthpiece 7 when the rim 9 is positioned thereon, thereby, to effectually prevent accidental displacement of the member 17. In positioning the cap on the mouthpiece of a telephone, one end of the wire is inserted in the groove 13 with the opposite end or finger piece 15 thereof projecting through the recess 16, after which the intermediate portion of the wire is 100 pressed laterally within the seating groove 105 110.

- 13, thus to form a circumferential lock and effectually prevent the removal of the cap. When it is desired to detach the cap, it is merely necessary to exert a slight lateral 5 pull on the finger piece 15 when the locking member or wire 14 will become disengaged from the seating groove 13 so as to permit the cap to be readily removed from the mouthpiece.
- 10 The device may be made in different sizes and shapes and nickelated, japanned or otherwise coated so as to give the same a neat and ornamental appearance.
- Having thus described the invention, what 15 is claimed as new is:
1. The combination with a mouthpiece, of a cap engaging the mouthpiece and having a circumferential groove formed therein and intersected by a transverse recess, a strip of 20 antiseptic material interposed between the cap and mouthpiece, and a locking member seated in said groove and provided with an angular finger-piece adapted to enter said recess.
  - 25 2. The combination with a mouthpiece, of a cap engaging the mouthpiece and having a circumferential groove formed therein and intersected by a transverse recess, a strip of material carried by the cap and saturated 30 with a soluble germicide which will dissolve in the moist spray thrown out in talking and render the same sterile, and a locking member engaging the groove in the cap and provided with an angular finger piece extending 35 through the recess in said cap.
  3. The combination with a mouthpiece, of a cap having an opening formed therein and defining an inwardly extending flange, there being a circumferential seating groove 40 formed in the cap and intersected by a transverse recess, a strip of material interposed between the flange and the adjacent edge of the mouthpiece and saturated with a soluble germicide which will dissolve in 45 the moist spray thrown out in talking and

render the same sterile, and a spring locking member seated in the groove and provided with a finger piece extending through the recess in said cap.

4. The combination with a mouthpiece, of 50 a cap having an annular flange provided with a circumferential seating groove and having its face formed with an opening defining an inwardly extending flange, the metal forming the cap being inclined in the 55 direction of the mouthpiece between the outer and inner flanges, there being a recess formed in the outer flange and intersecting the seating groove, a locking member seated in the groove and formed of a single length 60 of spring wire, one end of which is bent laterally to form a finger piece adapted to project through the recess in said outer flange, and a strip of material carried by the cap and saturated with a soluble germicide, said 65 strip of material being clamped in engagement with the adjacent end of the mouthpiece by contact with the inclined face of the cap.

5. As a new article of manufacture, a disinfecting cap for telephone transmitter mouthpieces, comprising a rim having an inwardly extending circumferential flange and an outer flange provided with a circumferential seating groove, there being a 75 recess formed in the outer flange and intersecting the groove, a strip of antiseptic material seated in the rim, a reinforcing strip secured to said material, and a resilient locking member seated in the groove in the outer 80 flange and having one end thereof bent laterally to form an angularly disposed finger piece extending through the recess in the rim.

In testimony whereof I affix my signature in presence of two witnesses.

FRANK H. PECK. [L.S.]
